ELECTRICAL PRECIPITATION

Harry J. White, Cambridge, Mass., assignor, by direct and mesne assignments, of one-half to Research Corporation, New York, N. Y., a corporation of New York, and one-half to Western Precipitation Corporation, Los Angeles, Calif., a corporation of California

Application June 5, 1943, Serial No. 489,833

10 Claims.

(Cl. 183—7)

This invention relates to the electrical precipitation of suspended particles from gases and is particularly directed to improved collecting electrode structures for electrical precipitators and to electrical precipitators including the new collecting electrode structures.

Briefly, the operation of electrical precipitation consists in passing gases, containing suspended fine particles of either solid or liquid, through an electric field in which the particles become electrically charged by attachment of electrons or ions and are then attracted to an electrically charged member upon which the charged particles are collected. It has been common practice to effect charging of the suspended particles by passing them between two opposed electrodes between which a high potential difference is maintained, one of the two electrodes being a discharge electrode at which there is silent or corona electrical discharge that ionizes the gas and causes the suspended particles to become charged with the same electrical sign as the discharge electrode. This is termed charging action.

In the "single stage" type of precipitator, the charged particles migrate under the influence of the electric field between the electrodes toward the other electrode which is a non-discharge electrode of extended surface, and collect or become precipitated upon the surface of that electrode which is consequently termed the collecting electrode. In the "two-stage" or "separated field" type of precipitators, the gas containing all or a substantial proportion of the charged particles passes into a second or precipitating field, typically maintained between opposed non-discharge electrodes, and, under the influence of the precipitating field, the charged particles migrate to one of the electrodes between which the field is maintained and are deposited thereon. The latter electrode is likewise termed a collecting electrode. The novel collecting electrode structures of the present invention may be advantageously utilized as collecting electrodes in either single-stage or two-stage precipitators.

In the following description and in the appended claims, the term "discharge electrode" will be understood to designate an electrode that facilitates corona discharge therefrom, because it has a configuration that establishes a sufficiently high potential gradient at or near its surface to create corona discharge before there is a disruptive discharge or spark-over. For this purpose the discharge electrode usually takes the form of a member of small surface area, such as a small diameter wire or a rod provided with sharp edges or

5 points, whereby there may be created in the immediate vicinity thereof a sufficiently high electric field intensity to cause ionization and corona discharge. The term "non-discharge electrode" will be understood to designate an electrode that minimizes or prevents corona discharge therefrom because it has a configuration that establishes a sufficiently low field concentration at or near the surface to suppress corona discharge at elevated 10 potentials lower than the voltage required for disruptive discharge or spark-over. For this purpose, a non-discharge electrode usually is one of extended surface area, substantially free from sharp corners or other parts of sharp surface curvature at all portions which are located within the electric field, so as to substantially avoid ionization or corona discharge at that electrode.

15 Dust particles in the gas stream become electrically charged in the ionizing field and there migrate to the collecting electrode under the influence of the electrical forces exerted on them, and when the particles reach and are precipitated on the electrode the electric charges are neutralized or lost. The layer of dust particles on 20 the electrode is exposed ordinarily to the gas stream which tends to blow off loose individual particles or agglomerations of particles, the erosion being a result of the gas velocity. The particles are held on the electrode more or less securely against erosion either by electrical forces or 25 by the physical properties of the particles themselves. When the collecting electrode is within the range of the charging field, as in the single field type of precipitator, the field recharges and 30 reprecipitates most of the particles that may be blown off the electrode, but even then some particles are blown along the electrode surface and off the outlet end of the electrode when the dust has such physical properties that the particles 35 offer little resistance to gas erosion. In the two-stage type of precipitator in which there is typically no corona discharge in the second or precipitating field, material removed from the collecting electrode by erosion is not recharged and 40 is carried out of the precipitator by the gases.

45 There are some dusts that are particularly hard to collect for this reason, one typical example being "fly ash" which is composed of particles that have a generally spherical shape and have very little inherent tendency to adhere to the electrode or to each other. Characteristics such as these facilitate erosion of the precipitated dust layer by the gas stream, the particles that are 50 picked up being carried away by the outgoing cleaned gases. Very little erosion takes place at

low gas velocities and may be neglected, though the rate increases slowly with increasing velocity up to some velocity termed the "critical velocity" above which erosion loss increases rapidly with an increase in velocity and becomes quite appreciable. It is probably true of most dusts, if not all, that there is a critical velocity above which losses are appreciable. The present interest centers particularly around dusts for which the critical velocity is relatively low, since the amount of these dusts carried into the outgoing gas stream is considerable and makes it difficult to obtain high overall collection efficiencies at economic velocities. Obviously, the critical velocity for a given dust limits the capacity of a given treater if a minimum collection efficiency is to be obtained.

This collection difficulty is inherent in the dust being collected and has the effect of reducing the capacity of a unit of a given size operating at a given normal efficiency, because of the limitation on dimensions required in order to keep the gas velocity below critical values. Expressed differently, the reduction in collection efficiency caused by erosion losses increases the size of the plant and equipment required to treat a given volume of gas without falling below a minimum efficiency.

A principal object of the invention is to provide an improved electric precipitator in which loss of collected material by erosion or redispersion in the gas stream is substantially reduced or eliminated.

A further object of the invention is the provision of an improved form of collecting electrode construction for electrical precipitators.

These, and other objects and advantages of the invention which will be clearly apparent from the following description, are attained by the provision in an electrical precipitator of a composite collecting electrode structure spaced from a complementary precipitating electrode structure to define a gas passage therebetween and comprising shield members defining a plurality of pockets along a lateral boundary of the gas passage, open to said gas passage but shielded by said shield members from the flow of gas therein, and electrode members, electrically insulated from the shield members, positioned in said pockets and electrically energized to impel charged particles in said pockets toward the surfaces of said shield members. The electrode members in the pockets may be either discharge or non-discharge electrodes. Particularly when the electrode members in the pockets are of the non-discharge type, they may be positioned and shaped to cooperate in shielding the pocket spaces from the adjacent gas stream. The potential difference maintained between the electrode members in the pockets and the shield electrodes is of the same polarity but substantially less than the potential difference maintained across the gas stream between the precipitating electrode structure and the collecting electrode structure.

The term "precipitating electrode structure" is used herein to designate electrode means opposed to and spaced from the collecting electrode structure and cooperating therewith to establish the electric field which causes charged particles to precipitate on the collecting electrode.

If the collecting electrode structure of the invention is embodied in a single stage precipitator, the complementary precipitating electrode structure will include discharge elements, while if the collecting electrode structure is embodied in the precipitating stage of a two-stage precipitator,

the complementary precipitating electrode structure will typically be of the non-discharge type.

In general, the average field strength between the electrode members in the pockets and the shield members may be of the same order as the average field strength between the precipitating electrodes and the collecting electrode structure.

The invention will be more particularly described for the purpose of illustration with reference to the accompanying drawings in which:

Fig. 1 is a sectional elevation of an electrical precipitator embodying the principles of the invention;

Fig. 2 is a plan view of the precipitator of Fig. 1 with the top cover plates removed;

Fig. 3 is a partial sectional elevation on line 3-3 of Fig. 2, and

Figs. 4 to 9 are diagrammatic representations of illustrative embodiments of the principles of the invention.

In Figs. 1-3, 10 is a precipitator casing provided with gas inlet 11, gas outlet 12 and a collecting hopper 13 for precipitated material.

Within the casing 10 are complementary precipitating and collecting electrode structures spaced apart to define longitudinal gas passages through the casing.

The precipitating electrode structures comprise 30 discharge electrodes 14, consisting of wires suspended from horizontal tubes 15 and maintained taut and in proper spaced relationship by tubes 16. Tubes 15 are carried on I-members 17 which are supported on insulators 18 and insulator bushings 19 contained in insulator housings 20. The precipitating electrode structure is energized through the insulator bushing 19.

The collecting electrode structure comprises a plurality of longitudinally extending vertical

40 plate members 21 supported by beam members 22 from the top of casing 10 and maintained in proper spaced relation by members 23 at their lower ends, and similar plate members 24 parallel to and alternating with plate members 21 but electrically insulated therefrom.

Plate members 24 are supported at their upper ends by means of rods 25 attached to the upper ends of the plate members and extending into engagement with tubes 26 which are carried on 50 I-members 27 supported from insulators 28 and insulator bushing 29 through which plate members 24 are energized. Plate members 24 are maintained in proper spaced position by means of tubes 31 which engage rods 30 attached to the lower ends of the plate members 24.

Plate members 21 and 24 cooperate to define material collecting pockets shielded from the gas stream in the gas passages between the precipitating and collecting electrode structures. The 60 lateral edges of the plate members are preferably rounded as shown to minimize corona discharge from the edges.

Baffles 32 aid in confining the gas flow within the interelectrode spaces.

65 The potential difference between the precipitating electrode structure and the grounded collecting electrode plates is preferably maintained at from 30 to 50 kv. with a spacing between the structures of 4 inches, for example, and a potential difference of the same polarity and of from 5 to 15 kv. is maintained between plates 24 and plates 21 with a spacing therebetween of 1 inch, for example.

If the precipitating electrode structure includes 70 non-discharge electrode members instead of the

discharge electrode members 14 of Figs. 1-3, the potential difference across the gas stream is preferably somewhat higher, for example, about 40 to 60 kv. for a 4-inch spacing of the electrode structures. If the non-discharge plate members 24 of the collecting electrode structure are replaced by discharge members spaced by one inch from the grounded shield members, a potential difference of about 8 to 10 kv. is preferably maintained therebetween.

A number of the many variations in the character and arrangement of the principal elements of the invention which are possible within the principles of the invention are diagrammatically illustrated in Figs. 4 to 9.

In Fig. 4 the plate members 24 of Figs. 1-3 are replaced by discharge electrode members 24' positioned in the material collecting pockets formed by plate members 21.

In Fig. 5 the discharge electrode members 14 of Figs. 1-3 are replaced by non-discharge precipitating electrode member 14'.

In Fig. 6 the plate members 21a and 24a corresponding to members 21 and 24, respectively, of Figs. 1-3, are convex in the upstream direction of the gas stream.

In Fig. 7 the plate members 21a, similar to the corresponding members of Fig. 6, are associated with discharge electrode members 24'.

In Fig. 8 the plate members 21b and 24b corresponding to members 21 and 24, respectively, of Figs. 1-3, are angular in section with the apex of the angle directed upstream.

In Fig. 9 the plate members 24 of Figs. 1-3 are replaced by non-discharge rod electrodes 24c.

The discharge electrode members 14 in the arrangements of Figs. 4, 6, 7, 8 and 9 may be replaced by non-discharge electrode members as in Fig. 5. Such constructions are particularly adapted for use as the second or precipitating stage of two-stage electrical precipitators.

It will be apparent from the foregoing description that the elements of the invention are subject to wide variation in form and arrangement without departing from the scope of the invention as defined in the appended claims.

I claim:

1. An electrical precipitator including opposed precipitating and collecting electrode structures spaced apart to provide a gas passage therebetween, the collecting electrode structure comprising a plurality of extended surface members spaced apart longitudinally of the gas passage to define a plurality of pockets open to the gas passage but shielded by said extended surface members from the flow of gas therein, and electrode members electrically insulated from said extended surface members, positioned in said pockets and maintained at an electric potential with respect to said extended surface members to impel charged particles in said pockets toward the surface of said members.

2. An electrical precipitator including opposed precipitating and collecting electrode structures spaced apart to provide a gas passage therebetween, the collecting electrode structure comprising a plurality of extended surface members spaced apart longitudinally to define a plurality of pockets open to the gas passage but shielded by said extended surface members from the flow of gas therein, alternate extended surface members being insulated and maintained at an electric potential with respect to the remaining extended surface members to impel charged particles in

said pockets toward the surface of said remaining members.

3. An electrical precipitator including opposed precipitating and collecting electrode structures spaced apart to provide a gas passage therebetween, the collecting electrode structure comprising a plurality of extended surface members spaced apart longitudinally of the gas passage to define a plurality of pockets open to the gas passage but shielded by said extended surface members from the flow of gas therein, and discharge electrode members electrically insulated from said extended surface members, positioned in said pockets and maintained at an electric potential with respect to said extended surface members to impel charged particles in said pockets toward the surface of said members.

4. An electrical precipitator including opposed precipitating and collecting electrode structures spaced apart to provide a gas passage therebetween, the collecting electrode structure comprising a plurality of parallel vertical plate members extending transversely to the gas passage and spaced apart longitudinally thereof and electrode members positioned between adjacent plate members and insulated therefrom.

20 5. An electrical precipitator including opposed precipitating and collecting electrode structures spaced apart to provide a gas passage therebetween, the collecting electrode structure comprising a plurality of parallel vertical plate members extending transversely to the gas passage and spaced apart longitudinally thereof and extended surface electrode members positioned between adjacent plate members and insulated therefrom.

25 6. An electrical precipitator including opposed precipitating and collecting electrode structures spaced apart to provide a gas passage therebetween, the collecting electrode structure comprising a plurality of parallel vertical plate members extending transversely to the gas passage and spaced apart longitudinally thereof and discharge electrode members positioned between adjacent plate members and insulated therefrom.

30 7. An electrical precipitator including opposed precipitating and collecting electrode structures spaced apart to provide a gas passage therebetween, the collecting electrode structure comprising a plurality of parallel vertical plate members extending transversely to the gas passage and spaced apart longitudinally thereof and extended surface electrode members positioned between adjacent plate members and insulated therefrom.

35 8. An electrical precipitator including opposed precipitating and collecting electrode structures spaced apart to provide a gas passage therebetween, the collecting electrode structure comprising a plurality of parallel vertical plate members extending transversely to the gas passage and spaced apart longitudinally thereof and discharge electrode members positioned between adjacent plate members and insulated therefrom.

40 9. An electrical precipitator including opposed electrode structures spaced apart to provide a gas passage therebetween, electric circuit means for establishing an electric field between said opposed electrode structures, one of said electrode structures comprising extended surface elements defining a plurality of pockets open to the gas passage but shielded from the flow of gas therein and intermediate elements positioned in said pockets, and electric circuit means for establishing an electric field between said intermediate elements and said extended surface elements of the same polarity and approximately the same average strength as said first electric field.

45 10. An electrical precipitator including opposed electrode structures spaced apart to provide a gas passage therebetween, electric circuit means for establishing an electric field between said opposed electrode structures, one of said electrode structures comprising extended surface elements defining a plurality of pockets open to the gas passage but shielded from the flow of gas therein and intermediate elements positioned in said pockets, and electric circuit means for establishing an electric field between said intermediate elements and said extended surface elements effective to maintain an electric discharge therebetween.

50 11. An electrical precipitator including opposed precipitating and collecting electrode structures

spaced apart to provide a gas passage therebetween, the collecting electrode structure comprising a plurality of extended surface members spaced apart longitudinally of the gas passage to define a plurality of pockets open to the gas passage but shielded by said extended surface members from the flow of gas therein, and electrode members electrically insulated from said extended surface members, positioned in said pockets at a distance from said extended surface members substantially less than the distance between said collecting electrode structure and said precipitating electrode structure and maintained at an electric potential with respect to said extended surface members to impel

15

charged particles in said pockets toward the surface of said members.

10. An electrical precipitator including opposed precipitating and collecting electrode structures spaced apart to provide a gas passage therebetween, the collecting electrode structure comprising a plurality of parallel vertical plate members extending transversely to the gas passage and spaced apart longitudinally thereof by a distance substantially less than the distance between said collecting electrode structure and said precipitating electrode structure and electrode members positioned between adjacent plate members and insulated therefrom.

HARRY J. WHITE.
